Applicant claims that the subject matter of this application is a division of application Serial No. 720,813, filed January 8, 1947, and that the present application is a continuation-in-part of application Serial No. 19,077, filed January 2, 1948, and that the subject matter of the present application is a division of application Serial No. 720,813.

UNITED STATES PATENT OFFICE

2,611,197

PORTABLE SECTIONAL IRONING BOARD

Alpha Perry Lantz, Washington, D. C.

Original application January 8, 1947, Serial No. 720,813. Divided and this application April 5, 1948, Serial No. 19,077

3 Claims. (Cl. 38—139)

1

This application is a division of application Serial No. 720,813, filed January 8, 1947.

This invention relates to an improved portable sectional ironing board and has for its object the provision of such a board particularly designed for folding its sections upon themselves to bring them into superimposed relationship enabling compactness and of a size suitable for accommodation and carrying in a suitcase or similar relatively small package.

In a companion case, Serial No. 719,799, filed January 2, 1947, the fundamental invention has been disclosed, the preferred embodiment there being means enabling the folding of the outer section under an inner section, the preferred embodiment in the present instance incorporating novel means enabling the folding of the outer section of the board over on top of the board to lie flat upon the inner section thereof.

The instant form or embodiment of the invention comprises the inner and outer sections adapted in use to have their upper or ironing surfaces flush, or in a common plane, as is quite necessary in an ironing operation, the two sections being connected by a hinging mechanism functioning, when the board is extended, to have the flush upper surfaces, as stated, but also enabling the complete folding back of the outer section onto the upper section to lie parallel with each other when in nested or stored condition.

The embodiment of the invention referred to is illustrated in the accompanying drawings forming part hereof and the details in the construction will be apparent from an inspection thereof together with the detailed description hereinafter contained.

In the drawings:

Figure 1 is a top plan view of the ironing board with its sections extended as in ironing operation.

Figure 2 is an edge view of the same.

Figure 3 is a central longitudinal section through the board when folded into compact form.

Figure 4 is a transverse section on the line 4—4 of Figure 1 looking to the left.

Figure 5 is a longitudinal section taken on line 5—5 of Figure 6 through the complete board in its unfolded or extended position.

Figure 6 is a bottom view of the ironing board as illustrated in Figure 1.

Figure 7 is a central longitudinal section of Figure 6.

Referring more specifically to the drawings wherein like reference numerals denote the same

parts in the respective views, 11 and 12 designate the two sections of the ironing board which, when in their unfolded or extended relationship have their upper surfaces flush or in a common plane, and contoured to present a combined shape for use after the fashion of a customary ironing board.

The section 11 has an end extension 13 of considerable length and extends entirely across the section, the same being depressed as at 14 for a depth equal to the thickness of the board 12 to provide a seat for the meeting end whereby the operating surfaces of the sections 11 and 12 will be in a common plane when being ironed upon.

These sections 11 and 12, and other parts of the ironing board, will be formed of some light material, such as metal, aluminum, or plastics, easily carried and preserved against rust, staining or the like.

When not in use, and to enable storage or carrying of the board from place-to-place in travel, the sections 11 and 12 are hinged together as will now be pointed out.

It is to be noted that the outer section 12 has a downwardly surrounding depending flange 15 to strengthen the same and at the inner ends to receive the end 13 of the section 11; and that the latter (the section 11) has corresponding downwardly depending flanges 16 with a downwardly and inwardly turned flange 17 on the other end of the board remote from the end 13, the same at the supporting end of the section 11, the outer end of the section 11, as at 18 being oppositely depressed inwardly to receive the end portions of the flange 15 on the section 12 so that the outer faces of the meeting flanges will be smooth or flush to avoid projecting edges to catch upon the apron or clothes of the operator.

Opposite ends 20 of a hinge rod 21, extending across and located beneath the section 11, project outwardly and have pivotal bearing in the vertical portions of the flanges 16, spacing sleeves 19 through which said ends 20 pass to said wall, abutting the inner faces of the flanges and offset U-shaped hinge portions 22 to prevent objectionable endwise play. The offset U-shaped hinge portions 22 pass through the free ends 23 of companion hinge members 24 in the form of integral extensions from the section 12 passed around the offset portions 22 and riveted at their return ends to the section 12 at 25. The hinge members 24 while extending from the surface of the section 12 are dipped sufficiently near their pivoted ends as at 26 to pass through

accommodating openings 27 in the section 11, to underlie and abut the top of the section 11 when the sections are unfolded and extended in ironing position (Figure 5), said openings 27 being extended outwardly to permit passage of the hinge ends 23 and offsets 22 of the pivot rod in an upward direction to enable folding of the outer section 12 back flat upon the inner section 11 (Figure 3), when the board is not in use and is to be stored or carried in a suitcase or package.

The portions of the side flanges 16, of the section 11, are widened downwardly as at 28 to afford sufficient metal and corresponding strength at the pivoted end portions 29 of the rod 21 therewith.

It will, of course, be appreciated that a suitable means for attaching the ironing board to a convenient piece of furniture, when desired for use, may be associated with the inner section of the ironing board, as fully disclosed and claimed in the parent application Serial No. 720,813, but inasmuch as the claims to this feature are retained in the parent case and no claim thereto is made herein, the illustrations hereof are confined to the divisible matter constituting the subject of this divisional case.

I claim:

1. A portable folding ironing board comprising inner and outer sections joined in overlapping relationship having ironing surfaces in substantially the same plane when in operative position, said inner section having a downwardly and inwardly extending flange depending from its sides and said outer section having a downwardly depending flange from its sides, said inner section having an extended depressed portion including said side flanges from the line of overlap in nested engagement within the ironing surface whereby the ironing surfaces of said sections form a substantially planar surface, said inner board being provided with spaced openings on its ironing surface and extending into the depressed portion, and means for pivotally connecting said sections together adjacent said line of overlap comprising a rotatable pintle having spaced crank portions, said pintle carried by said side flanges of said inner section and positioned beneath said openings, and hinge leaves extending from said outer section into the openings and adapted to be connected to said crank portions of the pintle pivotally engaging said inner section to support said outer section.

2. A portable folding ironing board comprising inner and outer sections joined in overlapping relationship having ironing surfaces in substantially the same plane when in operative position, said inner section having a downwardly and inwardly extending flanges depending from its sides and said outer section having a downwardly depending flange from its sides, said inner section having an extended depressed portion including said side flanges from the line of overlap in nested engagement within the ironing surface

whereby the ironing surfaces of said sections form a substantially planar surface, said inner board being provided with spaced opening on its ironing surface and extending into the depressed portion, and means for pivotally connecting said sections together adjacent said line of overlap comprising a rotatable pintle having spaced crank portions, said pintle carried by said side flanges of said inner section and positioned beneath said openings, and hinge leaves extending from said outer section into the opening, said hinge leaves having an offset portion and adapted to be connected to said crank portion of the pintle, said crank portions normally swing pivotally engaging the under side of the inner section in operative position to support the outer section and swing from said position through said openings when the sections are folded one upon the other.

20 3. A portable folding ironing board comprising inner and outer sections joined in overlapping relationship having ironing surfaces in substantially the same plane when in operative position, said inner section having a downwardly and inwardly extending flange depending from its sides and said outer section having a downwardly depending flange from its sides, said inner section having an extended depressed portion including said side flanges from the line of overlap in nested engagement within the ironing surface whereby the ironing surfaces of said sections form a substantially planar surface, said inner board being provided with an opening on its ironing surface and extending into the depressed portion, and means for pivotally connecting said sections together adjacent said line of overlap comprising a rotatable pintle having a crank portion said pintle being pivotally mounted on the underside of the inner section with the crank portion adapted to be positioned beneath said opening, and a hinge leaf extending from said outer section into said opening and having an offset crank seat extending beyond the opening said crank seat adapted to carry said crank portion beneath the inner section when in an unfolded position and to support the outer section and swing from said unfolded position through said opening when the sections are folded one upon the other.
